To all whom it may concern:

Be it known that I, Frederick Pittaro, a citizen of the United States of America, residing in Stamford, Connecticut, have invented a new, original, and ornamental Design for a Letter Opener or Similar Article, of which the following is a specification, reference being had to the accompanying drawings, forming part thereof.

Fig. 1 is a front perspective view of a letter opener showing my new design.

Fig. 2 is a side perspective view;

Fig. 3 is another front perspective view; and

Fig. 4 is a top perspective view thereof.

The back of the letter opener follows generally the appearance of the view given in Fig. 3 as it would appear with the cutting actuator bar removed and as indicated in Fig. 2.

I claim:

The ornamental design for a letter opener or similar article, as shown and described.
